UNITED STATES PATENT OFFICE

WILLIAM S. HAMM, OF ELKHART, INDIANA, ASSIGNOR TO THE ADLAKE COMPANY, OF CHICAGO, ILLINOIS, A CORPORATION OF ILLINOIS

WINDOW CONSTRUCTION

Application filed February 8, 1932. Serial No. 591,709.

The present invention relates to window construction, and has for its object the provision of improved means for holding a vertically movable sash tight in both its open and closed positions.

While the foregoing statement is indicative in a general way of the nature of the invention, other more specific objects and advantages will be apparent to those skilled in the art upon a full understanding of the construction, arrangement and operation of the parts constituting the improvement.

One form of the invention is presented herein by way of exemplification, but it will of course be appreciated that the invention is susceptible of embodiment in other structurally modified forms coming equally within the contemplated scope of the appended claims.

20 In the accompanying drawings:

Fig. 1 is an inside elevation of a window in which the invention is embodied;

Fig. 2 is an elevation of one of the inner sash stops, viewed in the plane of the sash;

25 Figs. 3, 4 and 5 are horizontal sections taken on the respective section lines indicated on Fig. 2;

Fig. 6 is a vertical section through the sash, taken on the line 6—6 of Fig. 1, showing the sash in its closed position;

Fig. 7 is a similar view, showing the sash in a released and partially raised position; and

Fig. 8 is a similar view, showing the sash in one of its stationary elevated positions.

Referring more in detail to the drawings, the window shown therein is provided, at each side thereof, with an outer stop 10 and an inner stop 11. Both stops are attached 40 to the usual post plate 12 and are spaced apart from each other far enough to permit the sash 13 to slide freely up and down therebetween. To insure proper spacing, the inner stop 11 is provided with a flange 14 which projects outwardly therefrom along the face of the post plate into engagement with the outer stop 11.

45 The inner stop 11, which preferably contains a curtain guide groove 15, is detachably secured to the post plate by screws 16 or

other suitable attaching means. This stop is of hollow sheet metal construction and the side of the same which faces toward the sash is open, thereby forming a channel 17. The channel 17 contains a lock rack 18 of novel construction, arrangement and operation. The rack 18 is pivotally mounted in the channel 17 on a cross pin 19, for a purpose which will hereinafter be explained. The rack is U-shaped in cross section, and is arranged with the back of the same facing toward the sash. A block 20 is positioned in the rack at the location of the pin 19 in order to reinforce the same. The pin 19 is preferably screwed into the inner stop 11, 55 with the head of the pin at the back thereof, whereby to permit detachment of the rack upon removal of the inner stop from the post plate. Below the pin 19 the rack 18 is provided at intervals with inclined seats 21 for 60 coaction with a pawl 22 which forms a part 65 of the lock on the sash.

The upper end of the rack 18 carries a shoe 23, which shoe is pivotally attached to the rack by a pin 24 and is adapted to engage flatly with the upper portion of the sash when pressed against the latter. The shoe 23 will be pressed against the sash when the rack 18 is engaged and oscillated by the pawl 22 of the lock. While the pawl 22 70 may be the nose of an ordinary throw-over type lock, it is shown herein as a pivotally mounted member which is cammed outwardly away from the sash by the beveled end of a bolt 25 when the bolt is projected into 75 engagement therewith by a spring 26. A finger piece 27 is connected with the bolt 25 in such a way as to retract the bolt and allow the pawl to return toward the sash when the finger piece is depressed. The particular 80 lock assembly shown forms the subject matter of an application of Walter E. Keller, Serial No. 591,530, filed on even date here-with, which application contains a more detailed description of the lock.

When the sash is raised and the finger pieces 27 of the locks at both sides are released, the pawls 22 will be forced by the spring-pressed bolts 25 to assume inclined positions in engagement with the racks 18 95 100

and will, upon being lowered into abutment with the nearest seats 21, oscillate the racks in the channels 17 under the weight of the sash. As a result of this, the shoes 23 will 5 force the upper portions of the sash against the outer stops 10, and the throwover effect caused by the inclined positions of the pawls and the weight of the sash will force the lower portions of the sash against the outer 10 stops, producing a tight, noiseless engagement therebetween. The sash is shown in one of such raised positions in Fig. 8.

To lower the sash from an elevated position, it is merely necessary to depress the 15 finger pieces 27 and give the sash a slight upward movement, whereby the pawls 22 will drop back into the plane of the sash and the shoes 23 will be released, allowing the sash to be moved freely and to be lowered without any resistance into its closed position. 20 The sash is shown in freed condition in Fig. 7.

When the sash reaches its fully closed position, releasing the finger pieces 27 will 25 allow the lower ends of the pawls 22 to be forced away from the sash into engagement with the back walls of the lowermost seats 28, and the pressure thereby exerted against the lower ends of the racks by the action 30 of the springs 26 in the locks will oscillate the racks far enough to force the shoes 23 against the upper portions of the sash and press the latter snugly against the outer stops. At the same time, the pressure exerted by 35 the pawls against the racks will react against the lower portion of the sash to press the latter tightly against the outer stops.

The lowermost seats 28 on the racks, 40 against which the pawls 22 engage when the sash is in its closed position, are preferably shallower and longer than the other seats, whereby to utilize the force of the springs 26 to the best advantage and prevent any 45 part of the weight of the sash from being supported by the rack, which support might otherwise prevent the sash from fully bottoming on the sill. The closed position of the sash is shown in Fig. 6.

The angle at which the bolts 25 bear 50 against the pawls 22 when the latter are projected is preferably such as to provide a substantial pressure of the pawls against the racks, which pressure is particularly desirable when the sash is in its closed position 55 and the pawls are bearing against the lower ends of the racks. The angle referred to also is preferably such as to prevent the pawls from backing up the bolts when pressure is applied to the pawls, thereby preventing 60 even the strongest wind pressure from forcing the lower portion of the sash inwardly away from the outer stops, and also preventing the sash from being raised from the outside.

To open the sash, it is merely necessary to

depress the finger pieces 27, whereupon the pawls 22 will drop back away from the lower ends of the racks, the pressure applied by the shoes 23 will be released, and the sash will be freed in its guides and can be raised 70 without appreciable effort.

It will be observed that the racks 18, instead of being straight, are of slightly angular form, and that the seats 21 in the racks are all of substantially the same size and 75 depth, with the possible exception of the lowermost ones, and are spaced equidistant from the sash when the latter is in sealed engagement with the outer stops 10. The inner stops 11 are preferably provided with 80 small tongues 29 which extend into the lower ends of the channels 17 and limit the outward swinging movements of the lower ends of the racks.

I claim:

1. In window construction, the combination with a window frame, and a vertically movable sash in the frame, of outer sash stops, inner sash stops, lock racks pivotally associated with the inner sash stops, shoes pivotally connected with the upper ends of the racks for engagement with the sash, and means for causing the weight of the sash when in raised position to move the racks in 95 such a way as to force the shoes against the sash.

2. In window construction, the combination with a window frame, and a vertically movable sash in the frame, of outer sash stops, inner sash stops having channels which open 100 toward the sash, lock racks pivotally mounted in the channels, shoes pivotally connected with the upper ends of the racks for projection from the channels into engagement with the sash, and means for causing the weight 105 of the sash when in raised position to move the racks in such a way as to force the shoes against the sash.

3. In window construction, the combination with a window frame having outer sash stops, and a vertically movable sash in the frame having normally projected lock members, of means actuated by the weight of the sash when the latter is in raised position and by the projection of the lock members when the sash is in lowered position for pressing the sash against the stops, said means including a pivotally mounted lock rack at each side of the frame for supporting the sash at any one of several predetermined elevations, and a pivotally mounted shoe at the upper end of the rack which is pressed by the latter against the upper portion of the sash upon the rack being engaged and oscillated by the lock member at that side of the frame. 115

4. In window construction, the combination with a window frame, and a vertically movable sash in the frame, of outer sash stops, inner sash stops, pivotally mounted lock racks associated with the inner stops and 120

provided below the pivotal axes thereof with a number of seats, shoes which are mounted on the upper ends of the racks, and spring-pressed lock members associated with the 5 sash for engagement with the racks at the locations of the seats, said lock members utilizing the weight of the sash when the latter is in raised position to oscillate the racks to press the shoes against the upper portion 10 of the sash and utilizing the spring force of said members when the sash is in lowered position to oscillate the racks for the same purpose.

5. In window construction, the combination 15 with a window frame, and a vertically movable sash in the frame, of outer sash stops, movable lock racks in opposition to the outer stops, shoes pivotally connected with the upper ends of the racks for engagement with 20 the sash, and means for causing the weight of the sash when in raised position to move the racks in such a way as to force the shoes against the sash.

In testimony whereof I have hereunto sub- 25 scribed my name.

WILLIAM S. HAMM.
